UNITED STATES PATENT OFFICE.

SYLVESTER C. WILLIAMS, OF EAST LIVERPOOL, OHIO.

MACHINE FOR CUTTING BARREL-HEADS.

SPECIFICATION forming part of Letters Patent No. 300,424, dated June 17, 1884.

Application filed December 7, 1883. (No model.)

To all whom it may concern:

Be it known that I, SYLVESTER C. WILLIAMS, a citizen of the United States, residing at East Liverpool, county of Columbiana, 5 and State of Ohio, have invented certain new and useful Improvements in Barrel-Head-Cutting Machines; and I do hereby declare the following to be a description of the same and of the manner of constructing and using the 10 invention in such full, clear, concise, and exact terms as to enable any person skilled in the art to which it appertains to construct and use the same, reference being had to the accompanying drawings, which form a part of 15 this specification, the principle of the invention being herein explained, and the best mode in which I have contemplated applying that principle, so as to distinguish it from other inventions.

20 In the drawings, Figure 1 is a side elevation of the machine. Fig. 2 is a detail view in vertical section of the main shaft with its connecting parts. Fig. 3 is a plan view of the saw-bed with saws and knives attached. 25 Fig. 4 is a detail view of one of the saws, showing the means of vertically adjusting the same.

A is the foundation, from which rise two upright posts, B B, at a suitable distance from 30 each other, connected at top by the cross-piece C. The cross-piece C is for the accommodation of the swinging crane D. The swinging crane D carries the binding-platen E.

F is a perpendicular screw fitted in boxes 35 f, with a bolt-head working loosely in the button e, and turned by the cross-lever f' for the depressing or raising of the platen E. The swinging crane D has its supporting-post G loosely journaled at top in the cross-piece C, and at bottom in the foundation A.

Under the platen E, when in position, is the bed-piece H, for the reception of the blanks. The bed-piece H is stationary by being firmly screwed to the top of the upright 45 shaft I, but is removable for the substitution of larger or smaller bed-pieces, as may be required for different-sized heads. Belted on the under side of each receiving bed-piece is an iron spider to stiffen it. The upright 50 shaft I springs from the supporting-step J,

in which it is firmly planted. The step J is firmly secured to the foundation A. At the foot of the shaft I, and immediately above the step J, is the loose thimble K, under which are inserted the prongs of the lever L. Above 55 the thimble K is the pulley M, on which plays the power-belt. The pulley M is firmly fastened to the under side of the circular table N. The table N carries the cutting-saws n and the beveling-knives n', which are upright and mounted on angle-irons. These saws and knives are movable by means of screws, bolts, or clamps for adjustment to varying concentric circles on the table N, as required for the cutting of larger or smaller 60 heads. The saws and knives are respectively adapted to be maintained at different points of vertical adjustment. The detail view of Fig. 4 represents the means employed 65 in connection with a saw, the same means being also employed with the knives. This table N revolves loosely on the shaft I, and is raised or lowered by means of the lever L. The lever L, pivoted in fulcrum l, is controlled by the eccentric lever l', or by other 70 convenient methods. When the blanks are laid on the receiving bed-piece H and secured by the platen E, the table N is lifted to its work by the lever L, and revolving by the applied power on the pulley M, the heads are 75 cut and beveled by the saws and knives.

Near to the outer edges of the receiving bed-piece H may stand two or more platforms, O, for the catching of what surplus strips or pieces are thrown off from the blanks. 85

What I claim is—

1. In a barrel-head-cutting machine, the combination, with a rotary table provided with upright sawing and cutting devices and means of raising or lowering the table, of a 90 circular bed-piece located above the latter, substantially as set forth.

2. In a barrel-head-cutting machine, the combination, with a rotary table provided with upright sawing and cutting devices and means for raising or lowering it, and a bed-piece located above the table, of a platen located above the bed-piece, and mechanism for vertically adjusting said platen, substantially 95 as set forth.

3. In a barrel - head - cutting machine, the combination, with a rotary table and a bed-piece above the table, of a platen provided with a mechanism adapted to swing it on and off from said bed-piece, substantially as set forth.

In testimony that I claim the foregoing to

be my invention I have hereunto set my hand this 23d day of November, A. D. 1883.

SYLVESTER C. WILLIAMS.
